No. 36,748.

Patented January 26, 1904.

UNITED STATES PATENT OFFICE.

HANS HOHNER, OF TROSSINGEN, GERMANY.

DESIGN FOR A MOUTH-HARMONICA.

SPECIFICATION forming part of Design No. 36,748, dated January 26, 1904.

Application filed August 1, 1901. Serial No. 70,514. Term of patent 14 years.

To all whom it may concern:

Be it known that I, HANS HOHNER, a citizen of Germany, residing at Trossingen, Württemberg, Germany, have invented a new, original, and ornamental Design for Mouth-Harmonicas, as shown in the accompanying drawings, in which—

Figure 1 is a view in perspective, and Fig. 2 is an end elevation.

What I claim as new, and desire to secure 10 by Letters Patent, is—

The ornamental design for a mouth-harmonica, as shown.

HANS HOHNER.
